DETERGENT

Fred Weaver Muncie, New Brunswick, N. J., and Kenneth L. Russell, New York, N. Y., assignors to Colgate-Palmolive-Peet Company, Jersey City, N. J., a corporation of Delaware

No Drawing. Application January 18, 1938,
Serial No. 185,622

13 Claims. (Cl. 260—400)

This invention relates to certain new chemical compositions and a method for their preparation. The compositions are particularly useful as wetting agents, foaming agents, detergents and emulsifiers, in treating textiles; in floating ores, as ingredients in laundry and textile preparations, and for many other purposes.

Many compounds are well known which are more or less useful for the above purposes, but nevertheless intensive efforts are being made to find compounds with more desirable characteristics and/or that can be produced at less cost. Among the known compounds that are useful as wetting agents, detergents, and the like, are a series of compounds which consist of glycerine, one hydroxy group of which has been replaced by a sulphate group, and another hydroxy group of which has been replaced by a fatty acid radical connected to the glycerine molecule through an ester linkage.

Compounds of this general type are described in Patent 2,023,387, granted to Benjamin R. Harris on December 3, 1935, and in applications for patents in the United States by Fred Weaver Muncie, filed June 27, 1935, and bearing Serial Numbers 28,711 and 28,712, now Patents Nos. 2,130,361 and 2,130,362, respectively, issued September 20, 1938. Other compounds which are generally similar except that they are true sulphonates instead of sulphates are also known, having been described, for example, in United States Patent 2,006,309, granted to Charles C. Clark on June 25, 1935.

According to the present invention, a new type of compound is provided which is generally similar to the type of compounds mentioned above, but which differs somewhat in its constitution and properties and possesses the particular advantage of being simply and easily produced from relatively inexpensive starting materials.

In the case of the known compounds mentioned, glycerine is an essential ingredient. Glycerine, however, is a relatively expensive raw material and, being an essential ingredient of many explosive compositions, becomes almost unobtainable in times of war. Under such circumstances, it is highly important that the use of glycerine be avoided. The patents mentioned make the general suggestion that glycols or other polyhydric alcohols, sugars, or the like, be substituted therefor, but this has not proved to be very satisfactory because most of these compounds are either too expensive or do not function as well as glycerine.

By following the principles of the present invention, the use of glycerine is avoided, a product being substituted therefor that functions exceptionally well for the present purpose, but which has not been found satisfactory for use in explosives, and which, as a consequence, is much cheaper than glycerine, particularly in times of war. Furthermore, this product which replaced glycerine is easily obtainable in a form that may be readily converted into a true sulphonate and this adds to the stability of the final material without involving the difficulty encountered in forming a true sulphonate from glycerine.

The material that is used in place of glycerine is beta methyl glycerine monochlorhydrin, which may be derived from isobutylene, which in turn may come from petroleum. It is well known that beta methyl glycerine may be made from isobutylene, the product being converted, in the course of its treatment, into beta methyl glycerine monochlorhydrin, which is then converted into beta methyl glycerine. By simply stopping the process at the point at which the product is in the form of the monochlorhydrin, the material to be used according to the present invention is obtained.

By combining with this material a fatty acid or a mixture of fatty acids, and affixing to it a sulphonate radical, a composition of the following structural formula is obtained:

In this formula "OOCR" indicates a fatty acid radical which may be either saturated or unsaturated, and preferably has between 5 and 21 carbon atoms in it, and "M" represents any suitable cation, for example, sodium, potassium, ammonium, triethanolammonium, calcium, or a heavy metal.

There is some possibility that the sulphonate, hydroxy and fatty acid radicals may not always attach to the beta methyl glycerine molecule in the same relative positions as those in which they are now shown, but may interchange their positions with one another. To indicate this in the formula, however, would involve considerable complication, and these radicals have therefore been attached in arbitrary positions, with the understanding that the obviously possible variations thereof are within the scope of this invention.

The preferred method of making the new type of composition consists in reacting beta methyl glycerine monochlorhydrin with an aqueous solution of a suitable sulphite, such as sodium sulphite or ammonium sulphite. This results in a salt of dihydroxy methyl propane sulphonic acid, which product may be reacted with a fatty acid or a mixture of fatty acids in a reaction vessel equipped to facilitate the removal of water 5 formed during the reaction. The best results have been obtained by heating these latter reactants, with agitation, at 175° C. to 225° C. for a period ranging from 4 to 15 hours. The 10 progress of the reaction is assisted by reducing the pressure so as to remove as much of the water as possible during the later stages of the 15 reaction.

Alternatively, the sodium salt of dihydroxy methyl propane sulphonic acid may be formed 20 as described above or by any other method and finally converted into the ultimate product by reaction with a fatty acid halide. In this case, the reaction takes place at a somewhat lower temperature, namely, from 75° C. to 125° C. 25 Preferably, the remaining halogen acid will be neutralized before any attempt is made to isolate the final product.

Still another way of making the same type of product is by forming a soluble salt of a halogen 30 hydroxy methyl propane sulphonic acid by partially sulphonating a beta methyl glycerine di-chlorhydrin and thereafter reacting the neutralized sulphonate with an alkali salt of a fatty acid.

The products made by the methods given are 35 not entirely pure, and usually contain a considerable quantity of inorganic or organic sulphates or chlorides formed by the neutralization of excess acid or acid freed in the reactions, but they 40 may be used for many of the purposes for which they are intended in the state in which they are prepared. Further purification may be effected by crystallization of the impure product from alcohol.

As a specific example of one method of forming 45 the new product, the following may be cited: To a boiling solution of 63 parts by weight (0.5 mole) of sodium sulphite in 222 parts of water, there was added dropwise 62.3 parts by weight 50 (0.5 mole) of beta methyl glycerine alpha chlorhydrin. The temperature of the mixture was maintained sufficiently high to boil off water for a period of one hour, and the sodium salt of beta methyl glycerine alpha sulphonic acid (sodium 1, 55 2 dihydroxy, 2 methyl propane, 3 sulphonate) resulted. This compound was heated with 102 parts by weight of cocoanut oil fatty acid for four hours at 200° C., agitation being maintained during the entire period. The water 60 evolved was allowed to escape and at the end of the reaction the product was purified by dissolving it in hot ethyl alcohol, filtering, and crystallizing from the filtrate. A nearly white, crystalline product resulted.

As a second example, 52 parts by weight (0.23 65 mole) of cocoanut oil fatty acid chloride was added to 40.5 parts by weight (0.25 mole) of the dry sodium salt of beta methyl glycerine alpha-sulphonic acid and the mixture heated at 100° C. to 120° C. with agitation for eight hours. At the end of this time the product was neutralized with caustic soda and purified as in the first example.

A foam test was made on samples of the material produced by each of the methods men-

tioned in the foregoing paragraph and it was found that 50 cubic centimeters of a 1% solution of the product, when placed in a 500 cc. graduated cylinder of 5 cm. diameter and shaken 20 times would produce a foam that reached the 475 cc. mark. Under similar conditions the sodium salt of a mono cocoanut fatty acid ester of glycerine mono sulphuric acid ester containing around 60% of sodium sulphate gave 450 cc. of foam.

A wetting test was also conducted by placing a piece of unwashed filter cloth in 100 cc. of a 1% aqueous solution of the new material in a 250 cc. beaker. The piece of filter cloth was carefully dropped into the liquid so as to lie flatly on the surface of the solution. At the end of 18 seconds the cloth was completely wet and sank to the bottom. Under similar conditions the glycerine product mentioned above sank in about the same time.

As has been said, the new materials may be used for deterging and wetting and for numerous purposes. They may be formed into beads, bars, flakes, chips, powders, or any other forms in which soap is ordinarily found, by the usual soap treating equipment. This is important, particularly, the ability of the product to form beads and bars, for by no means all sulphated or sulphonated materials can be prepared in these forms and the forms have, by extensive use in the soap industry, proved themselves to be highly desirable.

In addition, emulsions may be made by incorporating the new materials in mixtures of oleaginous and aqueous materials, with, of course, sufficient agitation and other treatment to disperse one of the phases into the other.

We claim:

1. As a new composition of matter, a chemical compound consisting of beta methyl glycerine, one hydroxy group of which has been esterified by a long-chain fatty acid and another hydroxy group of which has been replaced by a sulphinate radical.

2. As a new composition of matter, a chemical compound of the following formula:

in which R is an alkyl radical having from 4 to 20 carbon atoms, and M is a cation of the group consisting of sodium, potassium, calcium, ammonium and triethanolammonium.

3. As a new composition of matter, a chemical compound formed by reacting upon beta methyl glycerine monochlorhydrin with sodium sulphite and condensing the resultant product with a long chain fatty acid.

4. A process of forming a chemical compound that comprises reacting upon beta methyl glycerine monochlorhydrin with sodium sulphite and condensing the resultant product with a long chain fatty acid.

5. A process as described in claim 4 in which the condensation is performed at a temperature of 175° C. to 225° C. and under sub-atmospheric pressure.

6. A process of forming a new chemical compound that comprises converting beta methyl glycerine monochlorhydrin into a salt of dihydroxy methyl propane sulphonic acid and condensing the said sulphonic acid salt with a long chain fatty acid halide.

7. A process of forming a chemical compound that comprises converting beta methyl glycerine dichlorhydrin into a soluble salt of a halogen hydroxy methyl propane sulphonic acid and condensing said sulphonic acid salt with an alkali metal salt of a long chain fatty acid.

8. A process as described in claim 4 in which the final product is purified by crystallization from alcohol.

9. As a new composition of matter, a composition as described in claim 1 in the form of a bar or cake.

10. As a new composition of matter, a chemical compound as described in claim 1 in the form of beads.

11. As a new composition of matter, a chemical compound as described in claim 1 in the form of flakes or chips.

12. As a new composition of matter, a mixture of compounds of the formula:

5

in which OCR represents acyl radicals of cocoanut oil fatty acids, and M is a cation of the group consisting of sodium, potassium, calcium, ammonium, and triethanolammonium.

13. As a new composition of matter, a mixture of chemical compounds consisting of beta methyl glycerine, one hydroxy group of which has been esterified by a cocoanut fatty acid and another hydroxy group of which has been replaced by a sulphonate radical.
